PRESTRESSED TENDON ANCHOR MEANS
Richard P. Martter, 1239 Highland Ave., Glendale, Calif.
Filed July 17, 1962, Ser. No. 210,494
3 Claims. (Cl. 52—127)

This invention has to do generally with the prestressing of concrete structures.

Concrete bodies, whether columns, beams, floors, pipes or other forms are commonly prestressed by the use of tensioned elongated members, such as rods or wires, which place a compressive force on the body of concrete. Prestressing of the concrete is achieved either by pretensioning or by posttensioning such members. In pretensioning, the members are tensioned before the concrete is poured and are maintained in tension by external means until the concrete has reached the necessary strength and has bonded to the tensioned members. The latter are then released with the reaction transferring to the concrete body. In posttensioning, the wires, which are usually coated and enclosed in a conduit, are placed in the form but not tensioned and the concrete poured. When the concrete has cured sufficiently the members are tensioned with the force being transferred to the concrete body through anchor plates at the ends of the wires. The present application is particularly concerned with an improved method and means of prestressing by the post-tensioning method.

In posttensioning, since the tensioning of the wires takes place after the concrete body has been poured it is necessary to have access to the ends of the tensioning members. In the case of large floor slabs it has heretofore been the practice to provide recesses along the edges of the slab to expose the hardware at the ends of each tendon, or group of wires. This is a costly operation because of the amount of time and labor involved in constructing the specially shaped forms required to cast the recesses and subsequently required in filling in the recesses to make a flush edge along the slab after the tensioning has been accomplished.

An object of the present invention is to provide a novel method and means to overcome the disadvantages of the conventional method of prestressing and a method which enables casting the concrete body in its ultimate configuration thereby greatly reducing the cost of the structure.

Another object is to provide novel means for anchoring the stressed or tensioned wires including a novel stress washer and arrangement of wires therein and a novel anchor bar for use therewith.

A further object is to provide a novel stressing bar or anchor bar which is more efficient and less subject to failure than the wedge plates which are commonly used in conventional construction.

Still another object is to provide a novel tool for use in conjunction with a novel form of stressing washer which enables the insertion of an anchor bar after a tendon has been stressed even though the washer is recessed in the body of concrete and there is only limited working space therearound.

Another object is to provide a novel screw anchor having the advantages of the anchor bar referred to above and a novel tool for use therewith which makes it possible to maintain the washer supported against any return movement as the washer is pulled during the stressing operation thereby precluding injury to personnel or damage to the structure as might occur through failure of the jack or from some other cause.

A further object is to provide a novel screw anchor for use in conjunction with a washer which enables a "lift-off" reading to be taken conveniently and accurately as may be required.

2

These and other objects will be apparent from the drawing and the following description. Referring to the drawing:

FIG. 1 is an isometric view, partially in section, showing one end of a tendon and apparatus embodying the invention associated therewith embedded in the edge of a concrete body which is fragmentarily shown in section;

FIG. 2 is a vertical sectional view through the concrete body and apparatus of FIG. 1, together with a tool for stressing the tendon, the latter being shown stressed;

FIG. 3 is a view in the plane of line 3—3 of FIG. 2 but showing the completed stressed tendon with the anchor bar in position and the void filled with grout;

FIG. 4 is a fragmentary sectional elevation on line 4—4 of FIG. 2, but on a larger scale;

FIG. 5 is a sectional view on line 5—5 of FIG. 3, but on a larger scale;

FIG. 6 is a view similar to that of FIG. 2, but showing an alternate form of apparatus and showing the parts partially tensioned;

FIG. 7 is a view of the stressed tendon of FIG. 6; and

FIG. 8 is a cross sectional view on line 8—8 of FIG. 7, but on a larger scale.

More particularly describing the invention, referring first to FIGS. 1—5, numeral 11 designates a concrete body which may be a floor slab, a beam, post or other type of member. This body may be provided with a plurality of tendons for prestressing it and in FIG. 1, I show one end of a tendon designated 12 which may be assumed to extend through the body of concrete to its edge or end opposite the edge 13 shown in the drawing. As is conventional, the tendon itself is made up of a plurality of high-tensile steel wires 14 and these are anchored at each end in a stressing washer 15, the wires passing through the washer and being provided with button heads 16 formed thereon in any suitable manner to anchor the same.

When the wires of the tendon are assembled they are normally coated with a suitable lubricant and wrapped with a fiber-reinforced paper or the like to provide the sheath 18 shown in the drawings. Thus when the concrete is cast there will be a void within the sheath. I provide a conventional bearing plate 20 which has holes 21 therethrough to pass the wires. This bearing plate is recessed within the cast body of the concrete at the time the latter is poured. In order to provide working space exteriorly thereof I provide a tubular form or tube 22 which is shown as cylindrical, although it may be of different cross sectional shape, and this extends from the plate to the outer edge 13 of the concrete body. It is to be understood that the tendon and connected parts are located in the forms prior to the pouring of the concrete, and the tubular form member 22 is preferably attached to the bearing plate in order to keep the two parts properly oriented. The member 22 would have its outer end against the inner wall of the main form (not shown) which would define the edge 13 of the concrete body.

It will thus be apparent that a void or space 25 is provided in the concrete outwardly of the bearing plate but of less cross sectional area than the plate. This space provide access to the stressing washer 15 so that a tool may be inserted and attached to the washer for the purpose of tensioning the wires.

In FIG. 2 I show an adapter or tool 28 of hollow cylindrical form which has an interiorly threaded inner end portion 29 adapted to be threaded onto the washer 15, the latter having a threaded exterior surface for the purpose. The outer end portion 30 of the tool is solid and provided with a threaded socket 31 or other type of means for receiving the rod 33 of a hydraulic jack 35 such as shown in FIG. 6. With this construction the tool may be

threaded onto the washer and the jack operated to stress the wires 14 by pulling the washer out nearly to the outer edge 13 of the concrete body, as shown in FIG. 2.

One of the features of the invention is the provision of novel means for maintaining the tendon in tension and a novel way of inserting such means. The means comprises a bar 38 which is preferably rectangular in cross section and of appropriate length. The upper edge of the washer is recessed or slotted at 40 to partially receive the bar. Also the tool 28 is provided with a slot 42 which is made to register with the slot in the washer so that the bar may be slipped into the tool and forward through the slot in the washer and thence into final position in the space between the inner side of the washer and the bearing plate, as shown in FIG. 3. In this connection it should be noted that the wires 14 are arranged in the washer so as to provide a space at the top to receive the bar. This will be apparent from FIGS. 4 and 5 of the drawing which shows the pattern of the wires, as being generally U-shaped.

After the bar has been placed in position the jack 35 is removed as well as the tool 28 and the space or void 25 inside the tubular form 22 filled with grout 45 (FIG. 3) or other desired material.

Referring now to FIGS. 6 to 8, I show another form of the invention wherein the parts are recessed in a concrete body 11 in the same manner as previously described. However, in this form of the invention the washer, here designated 50, has an internally threaded central opening 51 which receives an externally threaded anchor bar or screw 52. I provide a tool 55 having an internally threaded inner end portion 56 for attachment to the washer as shown in FIG. 6. This tool has a threaded inner end portion 57 to receive the piston rod or ram 33 of a jack 35 which is used to stress the wires of the tendon.

One of the features of this particular form of the invention is the provision of a shaft 58 which is slidably and rotatably journaled in a central section 59 of the tool. The shaft may have a noncircular inner end 60 which seats in a correspondingly shaped socket 61 of the screw 52 so the latter can be turned by rotating the shaft. The outer end of the shaft is fitted with a universal joint 63 and a brace 64 extends therebeyond to facilitate operation.

In the operation of the apparatus, the tool 55 is attached to the washer and the jack operated to pull the washer and attached wires. During this operation the brace should be turned to cause the anchor screw to take up the slack and maintain the washer supported against return movement in event of failure of the jack or other equipment. When the wires have been tensioned sufficiently, the jack and tool are removed and the screw anchor bar 52 serves to maintain the parts in tension. The space outwardly of the bearing plate may be filled with grout 45 to complete the structure, as shown in FIG. 7.

Although I have illustrated and described preferred forms of my invention, I contemplate that various changes and modifications can be made therein without departing from the invention, the scope of which is indicated by the following claims.

I claim:

1. In a prestressed concrete body, a tendon comprised of a plurality of wires extending through the concrete body and terminating short of an outer face thereof; a bearing plate embedded in the concrete inwardly of said face and extending normal to the direction of the tendon; a stressing washer on the outer side of said bearing plate, the wires of the tendon passing through said plate and being anchored to said washer, said wires being in tension; and

a bar between said washer and said plate; a pair of said wires being spaced apart a distance greater than the minimum dimension of said bar defining a side opening through which said bar is insertable and the remaining wires being spaced apart a distance less than the minimum dimension of said bar providing an internal space for holding said bar in position after insertion through said side opening to support said bar in said space parallel with said wires and with one end of said bar abutting said washer and the other end abutting said plate thereby maintaining said wires in tension.

2. In a prestressed concrete body as defined in claim 1, a void in said concrete body extending from said bearing plate to said outer face, the clearance between said washer and said void being less than the smallest dimension of said bar;

a recess in the side of said washer, the clearance between the bottom of said recess and said void being greater than the smallest dimension of said bar, said recess receiving a portion of said bar while in longitudinal position permitting said bar to be moved past said washer into said space after placing said wires in tension.

3. In a prestressed concrete body, a tendon comprised of a plurality of wires extending through the concrete body and terminating short of an outer face thereof; a bearing plate embedded in the concrete inwardly of said face and extending normal to the direction of the tendon;

a stressing washer on the outer side of said bearing plate, the wires of the tendon passing through said plate and being anchored to said washer, said wires being in tension;

a void in said concrete body extending from said bearing plate to said outer face, the clearance between said washer and said void being less than the smallest dimension of an anchor bar;

a recess in the side of said washer, the clearance between the bottom of said recess and said void being greater than the smallest dimension of said bar, said recess receiving a portion of said bar while in longitudinal position permitting said bar to be moved past said washer into said space after placing said wires in tension;

a tool having a hollow, internally threaded inner end for threading onto said washer, said tool having a slot extending axially from its inner end for a substantial distance and adapted to be aligned to register with the recess in said washer, said tool being formed at its outer end for attachment of a jack, and said anchor bar inserted through said slot and said recess between said washer and said bearing plate when said tendon has been tensioned by pulling said washer outwardly of said plate.
